COLLAPSIBLE HOIST

James Roy Martin, Sr., Anderson, S. C.

Application October 20, 1947, Serial No. 780,922

4 Claims. (Cl. 212—61)

1

My invention relates to hoists, and more particularly to a hoist for use in roofing operations.

An important object of the invention is to provide a roofer's hoist which is well adapted for lifting light loads, and easy to manipulate.

A further object is to provide a hoist which is extremely simple in construction and easy to assemble and disassemble, thus reducing to a minimum the time required to move and set up the hoist.

A further object is to provide a roofer's hoist which is very light, yet strong and durable.

A still further object of the invention is to provide a hoist of the above mentioned class which has a boom that can be rotated horizontally through 360 degrees.

Other objects and advantages of the invention will be apparent during the course of the following description.

In the accompanying drawings, forming a part of this application, and in which like numerals are employed to designate like parts throughout the same,

Figure 1 is a perspective view of an assembled hoist in use upon a roof, the swinging boom being shown in alternate positions.

Figure 2 is an enlarged fragmentary central vertical section through the swinging boom and associated elements, parts in elevation.

Figure 3 is a view of the hoist disassembled.

Figure 4 is an enlarged fragmentary side elevation of the hoist, one of the base members being shown in section.

Figure 5 is a fragmentary plan view of the hoist.

Figure 6 is an enlarged fragmentary perspective view of the base, and

Figure 7 is an enlarged fragmentary vertical section through the foot of a brace, and associated elements.

In the drawings, where for the purpose of illustration is shown a preferred embodiment of the invention, the numeral 10 designates the roof of a building, or the like, upon which the hoist embodying the invention is mounted for use, as shown in Figure 1. The hoist comprises a base 11, including a pair of elongated horizontal base members 12 and 13. These base members 12 and 13 comprise parallel angle iron members or sides 14, rigidly connected at their outer ends by transverse braces or straps 15, preferably welded thereto. Similar transverse braces 16 are welded to the angle iron members 14 at points toward the inner ends of the same. Base plates 17 are rigidly mounted upon the

2

angle members 14, and disposed between the braces 15 and 16, and outwardly of the longitudinal centers of the base members 12 and 13. The base plates 17 carry central upstanding screw threaded studs 18, rigidly secured thereto, and these studs carry nuts 19. The upstanding vertical webs of the sides 14 are disposed outermost, and serve to stiffen the base members 12 and 13 against bending. Rigidly mounted upon the base member 12, by means of welding, or the like, and disposed at the inner end of such member, and extending laterally therefrom at one side of the same, is a flat horizontal support plate 20. This support plate 20 engages upon the tops of the vertical webs of the sides 14 of base member 12, as shown clearly in Figure 6, and is provided with an opening 21, above the transverse center of the base member 12. The support plate 20 extends over the base member 13, and slidably engages a plate or web 22, welded to the sides 14 of the base member 13, and flush with the tops of such sides. The plate 22 and support plate 20 have registering openings to receive a pivot bolt 23, carrying a nut 24. The bolt 23 serves to pivotally connect the base members 12 and 13 at their inner ends, so that they may swing from their open positions of Figure 1, to closed or collapsed positions where they are parallel, as in Figure 3. In the open position, the base members 12 and 13 are arranged at right angles.

Mounted upon the support plate 20, and detachably connected therewith, is an upright vertical column or standard 25, which is preferably cylindrical and tubular. This standard 25 carries an axial depending screw threaded stud 26 at its lower end, and rigidly secured thereto, and the stud 26 engages in the opening 21 in assembly. A nut 27 serves to rigidly clamp the standard 25 to the support plate 20. The standard 25 is provided with an external annular collar or stop 28, near its upper end but spaced downwardly therefrom. The stop 28 is rigidly secured to the standard 25 by welding or the like. The numerals 29 and 30 designate diagonal braces formed of sections of angle iron. These braces have bottom flattened ends bent to form horizontal apertured attaching feet 31. The feet 31 receive the studs 18, and the nuts 19 serve to detachably connect the braces 29 and 30 to the base plates 17. The top ends of the diagonal braces 29 and 30 have horizontal flat heads 32 rigidly secured thereto, and these heads have circular openings 33 to engage over the top end of the standard 25 in assembly. In assembly, the lowermost head 32 engages the top of the

annular collar or stop 28, and the other head 32 engages upon the lowermost head 32, as shown. The diagonal braces 29 and 30 form with the base members 12 and 13 and with the standard 25 a rigid structure.

Rotatably mounted upon the top end of the standard 25 and slidably engaging upon the uppermost head 32, is a cylindrical tubular hub 34 of a triangular shape boom 35. The boom 35 comprises triangular frame members or sides 36 which are welded at their inner ends to the opposite sides of the hub 34. These sides 36 converge outwardly, as shown in Figure 5, and are rigidly connected at their outer ends. The sides 36 include top and bottom angle members 37 and 38, and diagonal braces 39, 40, 41, and 42. The sides 36 are of welded construction. The members 37 and 38 converge toward their outer ends, Figure 3, and the boom 35 is provided with a vertically disposed ring 43 at its outer end, and rigidly secured thereto. At its bottom end, the tubular hub 34 is provided with an external annular strap 45, welded thereto, and carrying a radial extension or lug 46, having an opening 47. The lug 46 is disposed in the same vertical plane as the boom 35, and directly beneath the same. The boom is free to rotate horizontally through 360 degrees.

A standard pulley 48 may be attached to the ring 43, as shown, and this pulley alone is used when the hoist is operated manually, as in Figure 1. A second pulley, not shown, may be attached to the apertured lug 46, and used with the pulley 48, when the hoist is power operated.

In use the hoist is very easy to assemble and is well adapted for roofing operations. It is light and may be shifted to the desired position on the roof after assembly. The longitudinal base members 12 and 13 have portions which extend outwardly of the attaching feet 31, as shown, and suitable weights may be placed upon the outer ends of the base members, as shown in Figure 1, to prevent the hoist from tipping when used.

When assembling the hoist, the hinged base members are swung open to their positions of Figure 1, where they are disposed at right angles. The standard 25 is then mounted upon the plate 20 and secured in place with the nut 27. The heads 32 of diagonal braces 29 and 30 are then slipped over the top end of the standard 25 and engage upon the stop 28. The attaching feet 31 are then secured in place by means of the studs 18 and nuts 19. Finally, the boom 35 is mounted upon the upper end of the standard, and the hoist is ready for use.

When disassembled, the hoist is well adapted to be transported and the parts comprising the hoist are light.

It is to be understood that the form of the invention herewith shown and described is to be taken as a preferred example of the same, and that various changes in the shape, size and arrangement of parts may be resorted to, without departing from the spirit of the invention or the scope of the subjoined claims.

Having thus described the invention, I claim:

1. A roofer's hoist, comprising elongated base members adapted to be disposed substantially at right angles to each other, a support member secured to the inner end of one base member and projecting laterally therefrom and having an opening, means pivotally connecting the support member to the inner end of the other base member, a substantially vertical standard detachably mounted upon the support member and

including a part to engage in the opening, the standard being provided near its upper end with a stop, diagonal braces corresponding in number to the base members, one diagonal brace being detachably connected at its lower end to each base member, each diagonal brace being provided near its upper end with a head having an opening to detachably receive the upper end of the standard above the stop, said heads bearing against the stop, and a horizontally rotatable boom including a tubular hub, the tubular hub being adapted to receive the upper end of the standard and to bear against the heads.

2. A collapsible hoist, comprising elongated base members pivotally connected at their ends, a substantially vertical standard mounted upon one base member near the inner end of such base member and including a stop disposed near its top, diagonal braces corresponding in number to the base members, one diagonal brace having its lower end connected with each base member at a point remote from the standard, each diagonal brace including a head at its upper end having an opening to receive the upper end of the standard above the stop and to bear against the stop, and a horizontally rotatable triangular shaped boom including sides which converge outwardly and a tubular hub to receive the upper end of the standard above the heads of the braces and to bear against the heads, the boom being removable from the standard in an upward direction.

3. A collapsible hoist, comprising elongated base members adapted to be disposed at right angles to each other, a mounting plate secured to one base member near its inner end and pivotally connected with the other base member near the inner end of such base member, the mounting plate being provided with an opening, a substantially vertical standard detachably mounted upon the mounting plate and including a stud mounted within the opening, a nut carried by the stud, a collar secured to the standard near its upper end, diagonal braces, each diagonal brace being provided near its lower end with a foot and near its upper end with a head having an opening, one foot being detachably secured to each base member at a point remote from the standard, the opening of each head receiving the upper end of the standard above the collar, a triangular shaped boom including a tubular hub detachably mounted upon the upper end of the standard above the collar, the tubular hub bearing against the heads of the diagonal braces, a ring secured to the outer end of the boom, and a pulley supported by the ring.

4. A collapsible hoist, comprising base members, each base member including a pair of longitudinally spaced sides, a support plate arranged above and secured to the sides of one base member near the inner end of such base member and having an opening disposed between the sides of such base member, the support plate extending laterally beyond the base member to which it is attached and pivotally connected with the inner end of the other base member and extending over the other base member, a base plate arranged near the outer end of each base member and disposed between the sides of such base member and having an opening, diagonal braces, each diagonal brace being provided at its lower end with a substantially horizontal apertured foot and provided at its upper end with a substantially horizontal head having an opening, a substantially vertical standard mounted upon

the support plate, a stud carried by the lower end of the standard and passing through the opening of the support plate, a nut carried by the stud, a stop carried by the standard near its upper end, one foot being arranged adjacent to each base plate, a bolt extending through the opening of each base plate and through the adjacent apertured foot, the opening of each head receiving the upper end of the standard above the stop, and a boom having a tubular hub receiving the upper end of the standard above the stud.
